UNITED STATES PATENT OFFICE.

HENRY C. LOBECK, OF LAKE CITY, MINNESOTA, ASSIGNOR OF ONE-HALF
TO CHIPMAN W. MCELWAIN, OF SAME PLACE.

DESIGN FOR A TUB AND WASHBOARD CLAMP.

SPECIFICATION forming part of Design No. 31,555, dated September 26, 1899.

Application filed December 5, 1898. Serial No. 698,373. Term of patent 7 years.

To all whom it may concern:

Be it known that I, HENRY C. LOBECK, of Lake City, Wabasha county, Minnesota, have invented and produced a new and original Design for Washboard and Tub Clamps, of which the following is a specification, reference being had to the accompanying drawing, forming part thereof.

The drawing shows the invention in perspective, A representing the tub-engaging member secured to the member B by a stud 3.

The leading or material feature of my design consists of the shape of the member A.

I claim—

The design for a tub and washboard clamp, 15 substantially as herein shown and described.

In testimony whereof I affix my signature in the presence of two witnesses.

HENRY C. LOBECK.
